LÉON DIGNA, OF MONS, BELGIUM, ASSIGNOR TO ACIERIES DE HAINE ST. PIERRE ET LESQUIN, SOCIÉTÉ ANONYME, OF HAINE ST. PIERRE, BELGIUM.

RAILWAY RAIL FOR DETACHING BRAKE SKIDS.

Application filed February 25, 1927, Serial No. 171,026, and in Belgium February 27, 1926.

This invention relates to a siding rail for the retardation of wagons on open track.

As it is well known, in large railway yards where the marshalling of wagons for the formation of trains is carried out, the siding tracks are connected in different groups and the vehicles are generally pushed up a shunting hump, from which they descend by gravity to the track for which they are intended. The rows of wagons to be shunted may also come from one or more raised tracks, and the descent of the vehicles for classification operates in the same way by gravity.

15 Retardation of descending wagons coming from the hump or from the raised tracks is necessary to avoid violent shocks and hitherto for this purpose, track skates with two edges sometimes also called stop-blocks of 20 well known construction, have been used. The stop block being placed on the rail, the wheel of the wagon rises on to the sole of the block and then strikes against the upper inclinable edge of it so that a scotching 25 effect is produced and the wheel ceases to revolve; the wagon goes on, nevertheless, because of its acquired velocity and takes with it the skate, on which by virtue of its weight it exerts a high pressure, producing 30 braking on the rail and causing retardation or stoppage. Stoppage in shunting is habitually avoided by placing the skate in advance of the crossings of the rails, the arrangement of which generally allows of the 35 skating to one side of the stop-block after having sufficiently retarded the wagon, which continues to run towards its place.

This system of scotching at the crossing of the tracks by means of a doubled edged block presents certain serious inconveniences.

(1) It causes rapid wear of the frogs.

(2) It gives rise to jamming and deformation of the skates in the worn and bent part of the point frogs.

(3) It causes derailments of wagons, and accidents (slanting collisions) through too pronounced braking at the entrance to the sidings, when, during heavy pressure of work, the wagons follow one another closely.

All specialists know that scotching on open track is preferable to any other method because it gives by far the best results, but 55 they recognize that, under working condi-

tions, it cannot be used in yards where the tracks have too steep a slope and where it is impossible to withdraw the skate after stopping vehicles which recoil insufficiently.

The present invention has for its object to 60 avoid the inconveniences of the methods of scotching now in use and to render possible retardation on open track.

With this object in view the invention essentially consists in the special arrangements and combinations of parts as herein-after fully described and pointed out in the appended claims.

Referring to the annexed drawings which show as an example one embodiment of the 70 invention;

Fig. 1 represents an elevation of the apparatus adapted to a Vignoles rail.

Fig. 2 gives a plan of the rail.

Fig. 3 is a section taken on the line 75 III—III in Fig. 2.

Fig. 4 is a section taken on the line IV—IV in Fig. 2.

The rail *a* shown, the profile of which corresponds to that of the track rails, is fitted 80 with a head *b* which, at a particular point, *c* for example, of the middle of the rail, is bent towards the outside of the track as shown at *d*, its faces *e* and *f* remaining parallel, and a groove *g* with its side also 85 parallel being made against the bent part *d* of the rail head.

The dimensions of this groove are sufficient to allow the edge of the skate to pass 90 as described hereafter.

Beyond the bent part *d* of the rail-head, the rail is provided with a second head *h* placed in continuation of the track and ending in a point *i* the end of which slopes 95 downwards.

The bent part *d* of the rail head has a slight slope downwards towards the outside of the track as shown at *k* in Figs. 3 and 4.

A rail of this form is inserted in the track, and the retarding skate is placed in the 100 ordinary way on the rail-head *b* at a convenient distance in advance of the bent part *d* of the head. Under these conditions, when the wheel of a wagon rises on to the skate and causes the latter to slide on the rail-head 105 this stop block, when it reaches the point *c*, is deviated by the head *d*; the right-hand edge of the skate following the outer face *e* of the head *d*, while the left-hand edge of the skate engages in the groove *g*. 110

The momentum of the wagon of which the front wheel is scotched on the retarding skate, and the slope k of the end of rail-head d allow the skate to be easily ejected 5 to the side of the track after the desired retardation of the vehicle has been obtained.

In the drawing, the chain dotted lines in Fig. 2 represent the position of the retarding skate l , the skate being supposed to be 10 on the bent part d of the rail head.

During this operation, the tyre of the 15 of the wagon wheel, after propelling the skate l into the groove g , remains in contact with the rail-head d as far as the beginning of the slope k , and then comes into contact with the point i of the rail-head h at a part sufficiently strong to support the weight of the vehicle.

This siding rail secures the following 20 notable advantages:

(1) It enables efficient and well-judged retardation of wagons to be obtained at a chosen position where they cannot recover their speed.

(2) It avoids jamming and deformation 25 of the stop blocks in the point frogs as well as derailment of wagons sometimes caused by these inconveniences.

(3) It eliminates the wear of track parts 30 that is noticeable when retardation takes place at point frogs by the common methods of scotching.

(4) It avoids the derailment of wagons and the accidents resulting from too pronounced retardation.

(5) It considerably reduces (a) damage 35 to wagons and goods (b) breakage, wear or deformation of the skates.

(6) Its use requires no more work than 40 that of laying an ordinary rail.

(7) It allows bolts, distance blocks and check rails to be dispensed with and therefore requires no maintenance.

(8) It is adaptable to all kinds of rails, 45 indifferently for the right-hand or the left-hand rail of a track.

(9) It enables brakemen of the first group to be dispensed with in modern yards, where the profile is methodically inclined.

What I claim is:

1. In a siding rail for the retardation of wagons, on open track in combination a rail-head, this rail-head being interrupted by a groove extending from one face to the other of the said rail head and a projection parallel to the said groove whereby a stop-block placed on the rail and carried along by a vehicle is laterally ejected.

2. In a siding rail for the retardation of wagons, on open track in combination a rail-head, this rail-head being interrupted by a groove extending from one face to the other of the said rail head and a bent of the rail-head towards the outside parallel to the said groove whereby a stop-block placed on the rail and carried along by a vehicle is laterally ejected.

3. In a siding rail for the retardation of wagons on open track in combination a rail head, this rail head being interrupted by a groove extending from one face to the other of the said rail head and a bent of the rail towards the outside parallel to the said groove, the said bent sloping downwards from the rail-head to the flange of the rail 75 whereby a stop-block placed on the rail and carried along by a vehicle is laterally ejected.

In testimony whereof I have affixed my signature.

LÉON DIGNA.
